HOLDER FOR CARTRIDGES

Samuel Wiley, Metuchen, N. J.

Application February 19, 1934, Serial No. 711,980

6 Claims. (Cl. 42—1)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a holder for cartridges.

When a holder for discharging a projectile is to be aimed at a target it usually has the form of the conventional pistol with a hand-grip at 10 an angle to the barrel for the purpose of facilitating aiming. In this type of weapon the recoil is absorbed by the arm of the operator and the capacity of the operator to absorb the recoil of the piece is a limiting factor on the size 15 and range of the projectile.

When the projectile, such as a signal or flare, is not to be aimed at a target but is merely to be fired in a general direction, there is no purpose in providing angularity between the hand-grip and barrel.

20 The principal object of the present invention is to provide a holder in which the barrel and handle are on substantially the same axis whereby by the butt of the handle may be placed on any 25 convenient support to absorb the shock of recoil. A novel and inexpensive firing mechanism is mounted in the handle.

The invention is also directed to a simple provision for holding the cartridge case in the barrel and for subsequently extracting the case whereby the operations of loading, firing and extracting may be performed with one hand.

With the foregoing and other objects in view, 35 the invention resides in the novel arrangement and combination of parts and in the details of construction hereinafter described and claimed, it being understood that changes in the precise embodiment of the invention herein disclosed 40 may be made within the scope of what is claimed without departing from the spirit of the invention.

A practical embodiment of the invention is 45 illustrated in the accompanying drawing, where-
in:

Fig. 1 is a longitudinal sectional view of a 50 holder constructed in accordance with the invention.

Fig. 2 is a reduced view in elevation of the 55 holder.

Fig. 3 is a view in elevation of the cartridge.

Fig. 4 is a view showing the position of the 55 parts of the firing mechanism after the hammer has been fired and showing the position of the

hammer in dotted lines at the moment of its release.

Referring to the drawing by characters of reference, the improved holder consists generally of a handle A and a barrel B in prolongation of the 5 handle and on substantially the same axis. In the preferred embodiment of the invention the handle and barrel are separate members so that they may be readily connected, the specific connection consisting of a threaded stem 5 on the 10 handle receivable in a threaded aperture 6 in the base 7 of the barrel.

The stem is provided with a counterbored recess 8 opening into a chamber 9 in the handle, and housing a firing pin 10. The firing pin is 15 normally held in retracted position, with its rear end projecting into the chamber 9, by means of a spring 11, one end of which is seated on a collar 12 of the firing pin and holds the collar against an annular shoulder 13 of the recess 20 8. The other end of the spring is seated on a plug 14 threaded into the recess 8 and having a central aperture 15 for guiding the front end of the firing pin.

Positioned within the chamber 9 and directly 25 in rear of the firing pin is a hammer 16 having an arm 17 which is apertured to receive a mounting pin 18 supported by the handle. The arm is preferably provided with a slot 19 for receiving a sear 20 mounted on the pin 18. A 30 flat spring 21 secured to the hammer by a screw 22 has one end engaging the sear and serves to hold the sear with its inner side 20a against the hammer and in a position of non-rotative engagement therewith.

A safety lever 23 working in a slot 24 in the handle is mounted on a pin 25 at its upper end and has a foot 26 engaging a recess 27 in the hammer. The lower end of the lever is provided with a slot 28 receiving a pin 29 fixed in 40 the handle and limiting movement of the lever. A flat spring 30 disposed in the chamber 9 and secured by a screw 31 engages the slotted end of the lever and normally maintains the foot 26 in engagement with the hammer.

A trigger lever 32, working in a slot 33 in the handle opposite to the slot 24 accommodating the safety lever 23, is mounted on a pin 34 at its lower end. A spring 35 secured to the trigger by a screw 36 has a curved extremity 37 acting on a curved face 38 of the hammer. The upper extremity of the trigger terminates in a foot 39 provided with a slot 40 for receiving a pin 41 fixed in the handle and limiting movement of the 55

trigger. A toe 42 on the foot 39 of the trigger is engageable with the sear 20.

The elements of the trigger mechanism are shown in normal position in Fig. 1, the firing pin being cocked and the hammer being held in safe or inoperative position. In grasping the handle, the hand of the operator encloses the safety lever 23 as well as the trigger lever 32. Pressure exerted on the trigger lever 32 cannot be effective unless pressure is also exerted on the safety lever 23 to move it out of the path of rotation of the hammer. The inward movement of the trigger lever 32 acting on the sear 20 rotates the hammer about its pivot and compresses the spring 35.

As indicated in Fig. 4 the toe 42 of the trigger, moving on a radius greater than that of the sear, overrides the sear when the trigger indicated in the dotted lines is at the limit of its inward stroke. When the trigger is thus disengaged or released from the sear, the spring 35 acts to counterrotate the hammer and drive it against the firing pin. During this movement of the hammer the sear 20 has moved behind the toe 42 of the trigger.

Upon removing pressure from the trigger, the spring 35 moves the trigger outwardly and the toe 42 rotates the sear until it passes. The sear is returned to its normal position by the sear spring 21. When pressure is released from the safety lever 23 it is rotated by its spring 30 and its foot 26 engages the hammer.

The muzzle of the barrel B is formed with a counterbored recess 43 whose wall is engaged by an annular bead or corresponding projection 44 of a cartridge case 45. The frictional engagement of the bead against the wall of the barrel is sufficient to hold the cartridge against the blow of the firing pin. Except for this engagement the cartridge case has a loose fit in the barrel.

The forward portion of the cartridge case is provided with a flange 46 that extends over the front edge of the barrel. The exterior surface of the muzzle of the barrel is beveled as at 47 so as to expose more of the flange. The flange serves as a means for extracting the cartridge case from the barrel. It may be directly engaged by the hand of the operator or it may be caught on a more or less rigid article and extraction effected by pulling back on the holder A-B.

The cartridge case is provided with the usual primer 48 and the projectile 49 carried by the cartridge case is a flare or signal, the detail construction of which forms no part of the present invention.

When the holder is to be used in an airplane, the cartridges are carried in a rack so that the holder can be loaded by merely moving the barrel over the cartridge case until the bead or projection 44 is frictionally engaged by the barrel. The base of the holder is then placed on a convenient support and the firing mechanism actuated by contracting the hand. The operations of loading, firing and extraction of the empty cartridge case may be easily and quickly performed, using only one hand.

I claim:

1. A firing mechanism comprising a support constituting a handle and having slots in oppo-

site sides, a firing pin mounted in the support, a hammer within the support, a pivot pin for mounting the hammer, a sear mounted on the pivot pin of the hammer, a sear spring holding the inner side of the sear against the hammer, a safety lever disposed in one of the slots of the support, a pivot pin in the vicinity of the hammer for mounting the safety lever, means for normally holding the safety lever in engagement with the hammer, a trigger lever disposed in the other slot of the support, a pivot pin remote from the hammer for mounting the trigger, a spring secured to the trigger and acting on the hammer, and a foot on the trigger having a toe engageable with the sear. 15

2. A firing mechanism comprising a support constituting a handle, a firing pin carried thereby, a hammer for the firing pin, a hammer spring, a safety lever extending longitudinally of the support and engageable with the hammer, means 20 for pivotally mounting said lever in the vicinity of the hammer, a trigger lever extending longitudinally of the support, means for pivotally mounting said trigger remote from the hammer, and means on said trigger lever for engaging the 25 sear.

3. A firing mechanism comprising a support constituting a handle, a firing pin carried thereby, a hammer for the firing pin pivoted in the support, 30 a pair of substantially parallel levers on opposite sides of the support, means for pivotally mounting the opposite ends of said levers, means on one lever for engaging the hammer to hold it against pivotal movement, and means on the other lever for engaging the hammer to pivotally move the same. 35

4. A firing mechanism comprising a support constituting a handle, a firing pin carried thereby, a hammer for the firing pin pivoted in the support, a pair of substantially parallel levers on 40 opposite sides of the support, means for pivotally mounting the opposite ends of said levers, and means on the levers for engaging the hammer. 45

5. A firing mechanism comprising a support, 45 a firing pin mounted therein, a hammer within the support, a pivot pin for mounting the hammer, a sear mounted on the pivot pin of the hammer, a sear spring holding the inner side 50 of the sear in engagement with the hammer, a trigger lever carried by the support, a pivot pin remote from the hammer for mounting the trigger, and positioned so that the arc of movement of the trigger includes the arc of movement of the sear and a foot on the trigger having a toe 55 engageable with the sear, and a spring normally urging the hammer towards the firing pin. 60

6. A firing mechanism comprising a support, 60 a firing pin mounted therein, a hammer pivotally mounted in the support, a hammer spring, a sear pivotally mounted on the hammer and having a position of non-rotative engagement therewith, a spring normally holding the sear in such 65 position, a trigger lever pivotally mounted on the support so that its arc of movement includes the arc of movement of the sear, and means on the lever engageable with the sear.

SAMUEL WILEY.
